(57) **CLAIM**

The ornamental design for a personal underwater signalling and emergency device for divers, as shown and described.

DESCRIPTION

FIG. 1 is a front perspective view of a personal underwater signalling and emergency device for divers showing my new design;

FIG. 2 is a top view thereof;

FIG. 3 is a left side view of the signalling device, the right side view being a mirror image thereof;

FIG. 4 is a rear view thereof;

FIG. 5 is a rear perspective view thereof; and,

FIG. 6 is a bottom view.

The broken lines depict unclaimed environmental subject matter.
